UNITED STATES PATENT OFFICE

117,768

DESIGN FOR A COMBINATION CAN PUNCHER AND STOPPER

William H. Casebeer, Wenatchee, Wash.

Application July 4, 1939, Serial No. 85,842

Term of patent 3½ years

To all whom it may concern:

Be it known that I, William H. Casebeer, a citizen of the United States, residing at Wenatchee, Chelan County, State of Washington, have invented a new, original, and ornamental Design for a Combination Can Puncher and Stopper, of which the following is a specification, reference being had to the accompanying drawing, forming part thereof.

Fig. 1 is a side elevational view of a combination can puncher and stopper, showing my new design; Fig. 2 is a top view of the same; and Fig. 3 is an end view looking toward the right of Fig. 1.

Both sides of article shown in Fig. 1 are to have the same appearance.

I claim:

The ornamental design for a combination can puncher and stopper, as shown and described.

WILLIAM H. CASEBEER.
